Garrett Russell
By John O. Seifert, Atty.

UNITED STATES PATENT OFFICE.

GARRETT RUSSELL, OF ELSTERNWICK, AUSTRALIA.

MEANS FOR ORNAMENTING GLAZED PANELS OF, OR FOR, DOORS, WINDOWS, AND THE
LIKE SO AS TO OBTAIN LEAD-LIGHT EFFECTS.

Application filed April 30, 1923. Serial No. 635,497.

To all whom it may concern:

Be it known that I, GARRETT RUSSELL, a subject of the King of Great Britain, residing at Elsternwick, in the State of Victoria, 5 Commonwealth of Australia, have invented new and useful Improved Means for Ornamenting Glazed Panels of, or for, Doors, Windows, and the like so as to Obtain Lead-Light Effects, of which the following is a 10 specification.

This invention relates to an improved means for ornamenting glazed panels of, or for doors, windows, shop fronts, show-cases, book-cases and the like whereby lead-light 15 effects are produced in an economical and satisfactory manner.

The invention provides means for converting plain glass windows or doors into leaded lights of various designs including colored 20 panels, without requiring the glass to be removed from their frames or to be cut, and at relatively low cost.

The invention also includes means for economically preparing strips of lead into 25 required shaped and selected designs for affixture to windows and other glass surfaces to obtain the ornamental effect of lead-lighting.

Reference is made to the accompanying 30 drawings, wherein:—

Figure 1 is a view in elevation of a window ornamented with flexible metal strips, to obtain the effect of lead-lighting, according to the invention.

Figure 2 is a view illustrating a design formed from short lengths of lead or like flexible metal, firmly secured together, and adapted for affixture in unit form to a glass panel.

Figure 3 is a perspective view on an enlarged scale of two lead strips or fillets adapted to intersect each other and be interlocked in the formation of a decorative design.

Figure 4 is a fragmentary view in perspective of the lead strips or fillets—see in Figure 3—when in interlocked engagement.

Figure 5 is a sectional detail view illustrating means for affixing the lead strips, forming a selected design, to one surface of a window or other glazed panel.

Figure 6 is a plan view of a table employed to economically form lead strips into

a multiplicity of designs or patterns for subsequent affixture to glass panels to obtain lead-light ornamentation. 55

In these views 7 designates a window frame of conventional type fitted with a sheet of glass 8, which may either be plain, colored or embossed. This sheet of glass 60 is ornamented by having affixed to its outer surface, and also if desired to its inner surface, lead strips 9 which are grouped and arranged relatively to each other to provide a selected ornamental design. 65

The lead strips are concave as seen at 10, or they may be grooved, on their under-surface or glass side, to receive and bond a suitable cement indicated by 11, which cement is unaffected by moisture and is employed to 70 affix the metal strips to the glass sheet or panel so as to be free to all risk of displacement.

For the purpose of converting a glazed sheet, which is already in position in a window or like frame, to a leaded-light, the general outline of a design or pattern (such as, for example, that shown in Figure 1) 75 may be drawn upon, or a drawing thereof can be temporarily affixed to one surface of the glass panel, and short strips of lead, concaved, or grooved on its undersurface are cut, and then formed into the corresponding design or pattern and affixed by a cement to the opposite surface of the glazed sheet. 80 85

In order to provide a flush surface at the intersecting points of lead strips employed in the making of a selected design, gaps or recesses 12 are formed in said lead strips at required locations, whereby said strips, when fitted together, will interlock at their junctioning points—see Figures 3 and 4. Alternatively, said lead strips may be cut to the exact required lengths and be welded to the intersecting strips or fillets at their 90 95 abutment points.

A suitable bordering 13 preferably constituted of lead strips, is placed around the inside of the window or door frame and functions as an assembly integer to maintain the design elements firmly in position, and this bordering is rigidly secured to the window or door frame by means of tacks or like fastenings. 100

Figure 2 illustrates a representative design adapted for affixture as a unit to the 105

glazed panel of a window or door, and the outer or enclosing strips 14 of this design functions similarly to the bordering 13 by aiding in the affixture of the leaded-light 5 design to the glazed panel. It will be understood that the under-surfaces of the bordering 13 and enclosing lead strips 14 are, or may be, concaved to better hold the cement employed to affix the design or pattern to the glass surface.

If desired, portion or portions of the glass, such for example, as those portions indicated by 15 and 16 in Figure 2 can be colored by the application of suitable coloring agents or dyes to enhance the ornamental effect.

To facilitate the formation of the lead strips into required shapes and designs, I provide a flat table 17 constructed either of 20 metal, wood or other approved material, and as illustrated in Figure 6.

On the upper surface of this table there are formed a multiplicity of geometrical and other designs, including scrolls, curves, 25 ovals, rectangles, diamond and other shapes and shape sections required to form patterns or designs of all ordinary kinds followed in the art for ornamentation purposes.

It will be observed that the designs illustrated in Figures 1 and 2 are embodied in 30 the table surface, and that each design retains its individuality without interfering with that of other designs. These designs are obtained by forming in the table surface a multiplicity of grooves or slots 18 which 35 are adapted to freely accommodate the lead strips, and thereby enable the same to be shaped as required, even by inexperienced persons, within a short space of time. To 40 facilitate the insertion of the lead strips into said grooves or slots 18, entrance slots 19 are provided in the table surface at the termini of grooves or slots forming lines or groups of lines of a design.

45 Instead of grooving or slotting the table 17 as hereinbefore described, the designs and patterns of said table may be in high relief and formed by mounting on the table strips

of approved material in the required designs, grouping and arrangement.

50 A window or glazed panel ornamented according to my invention closely approximates in appearance the ordinary lead-lights, while it has amongst its advantages added strength imparted to the glass sheet, 55 the condition of being rain-proof, the impossibility of removing a pane by cutting the lead, as the whole of the glass is in one sheet, and the ease with which the window can be cleaned.

60 What I do claim is:—

1. The method for ornamenting a glazed panel to represent leaded-lights, which consists in shaping strips of flexible metal, fastening said strips together to form a selected 65 design, and then adhesively affixing said strips as a complete and single unit to the surface of the panel by the use of a cement, substantially as described.

2. The method for ornamenting a glazed 70 panel to represent leaded-lights, which consists in shaping strips of flexible metal, fastening said strips together to form a selected design, recessing said strips to allow them to interlock and to be of the same 75 thickness as the strips at intersecting points, and then adhesively affixing said strips as a complete and single unit to the surface of the panel by the use of a cement, substantially as described.

3. The method for ornamenting a glazed panel having a frame to represent leaded-lights, which consists in shaping strips of lead, assembling said strips upon a grooved 85 table, fastening said strips together while on the table to form a selected design, and then adhesively affixing said strips as a complete and single unit to the surface of the glazed panel by the use of a cement, substantially as described.

90 In testimony whereof I affix my signature in presence of two witnesses.

GARRETT RUSSELL.
